CIGARETTE DISPENSER

Roy H. Colomy, Springdale, Conn.

Application November 18, 1936, Serial No. 111,418

3 Claims. (Cl. 312—77)

This invention relates to improvements in cigarette dispensers.

Heretofore various cigarette dispensers have been proposed, and some of these have been quite successfully received by the trade. However, most of these previously proposed structures were somewhat cumbersome, and were costly to manufacture.

It is an object of the present invention to provide a very simple cigarette dispenser, having very few parts, which can be manufactured very economically.

A feature resulting from the attainment of this object is the provision of a cigarette dispenser comprising only two parts. One of these parts is a base, made of wood, Bakelite or any other desirable material, which pivotally supports a cigarette storage container.

In many of the previously proposed cigarette dispensers special spring mechanisms were provided adapted to work directly upon individual cigarettes or the entire group of cigarettes in a container to eject the same. Such proposals have the disadvantage of failing to work properly when tobacco particles accumulate in the section of the device normally occupied by the spring or the usual movable pad associated with the spring. Also, in some cigarette dispensers where a spring and spring pad structure is provided it is desirable to have the spring as light as possible in order to prevent crushing cigarettes. Because of the light pressure initially built into such spring mechanisms there have been instances where the spring failed to lift or otherwise eject the cigarettes shortly after the device was put into use and especially when even a little resistance was imposed thereon as by slight particles of tobacco.

It is an object of the present invention to provide a cigarette dispenser in which there is no need to provide spring structures working directly upon a cigarette or cigarettes to eject the same.

Features flowing from the attainment of this latter object include the provision of a structure adapted to effect the delivery of cigarettes, one at a time, by gravity; such structure including a simple storage container adapted to house a plurality of cigarettes and to deposit one cigarette to a depositing channel each time the container is pivotally moved relative to a base.

With some forms of cigarette dispensers heretofore proposed parts of the dispenser would be left in an open position when a cigarette was ejected, allowing warm circulating air in a room to adversely get at and dry out the cigarettes in the device.

It is another object of the present invention to provide a cigarette dispenser in which the storage container for the plurality of cigarettes will be fully enclosed, to prevent the cigarettes from drying out adversely, at all times.

The present invention includes the feature of a cigarette storage container enclosed fully when in depositing or nonwithdrawal position as well as when in nondepositing or withdrawal position.

Other features flowing from the above objects and from the present invention include the provision of novel spring means adapted to automatically return the cigarette storage container into a normal nondepositing or nonwithdrawal position, respectively; novel stops to limit movement of the container into the depositing and to the nondepositing positions; and, the provision of a novel structure adapted to carry a cigarette to a depositing position and to roll the cigarette automatically from the depositing position to a "pickup" position.

Other objects, features and advantages will appear hereinafter.

In the drawing:

Figure 1 is a perspective view of the simplest form of the present invention.

Fig. 2 is a side view, partly in section, of that form of the invention shown in Fig. 1.

Fig. 3 is a fragmentary view disclosing a structure for automatically returning the storage container to the nonwithdrawal position.

Fig. 4 is a fragmentary view of a slightly modified structure somewhat like that shown in Fig. 3.

Fig. 5 is a fragmentary view of a modified form of dispensing arrangement, wherein the cigarettes are moved one by one to a depositing position and automatically rolled into a "pickup" position.

Fig. 6 is a fragmentary and sectional view of the pivot for that form of cigarette dispenser disclosed in Figs. 1 and 2.

Referring now in detail to the drawing, the simplest and present preferred form of the invention, shown in Figs. 1 and 2, comprises a base 10 including a plate-like bottom 11 and an upper 45 delivery block 12. The base may be made of wood, Bakelite, metal or any other desired material, for economy or to achieve various ornamental effects. Preferably the base is made with the bottom and delivery block integral. However, these two sections may be made separately and glued or otherwise secured together as at 13.

Now, of particular importance, the base 10 pivotally supports a storage container 14, preferably of rectangular shape including walls 15, 16, 55

17 and 18 adapted to house a plurality of cigarettes 20. The container is preferably made to accommodate a usual pack of twenty cigarettes and a few extras which may be remaining in the 5 container previous to a reloading. As shown in Fig. 2, the walls of the container may be made of lightweight and inexpensive metal.

Referring to Figs. 1, 2 and 6, the walls 17 and 18 are provided with integral fingers 21 extending 10 down over the ends 22 and 23 of the block 12 to locate the container 14 laterally relative to the block 12. Also, these fingers 21 are preferably provided with integral embossed projections 24 adapted to snap into depressions 25 in the ends 15 22 and 23, thus providing a pivot connection 26 at the ends 22 and 23 of the block 12. This pivot connection may be very economically manufactured since the pivot parts are formed by the container and by the block. The pivot connections 26 on the fingers 21 and the walls 17 and 18 may be comparatively loose, or by having the 20 projections 24 narrower relative to each other than the spacing between the depressions 25 on the ends 22 and 23 sufficient friction may be provided to maintain the storage container 14 in any 25 position it is moved to on the base 10.

Although not absolutely essential a cover 27 may be provided at the top of the storage container 14 to fully enclose the cigarettes 20 therein.

30 The block 12 is provided with a depositing channel 28 including a slot extending longitudinally across the top of the block 12 as may be seen best in Fig. 2. Normally the storage container 14 is in a vertical and nonwithdrawal position relative to the base as shown by solid lines in Figs. 1 and 2 whereupon one of the cigarettes in the container will roll or drop into the depositing channel 28 shown in Fig. 2. The fingers 21 fully enclose the cigarette in the depositing channel 28 while the storage container is in the nonwithdrawal position. Thus, the walls, 35 top, block and fingers form a substantially airtight container. It will be apparent that all the cigarettes 20 in the storage container will be fully 40 enclosed against drying, and will be kept fresh 45 and moist at all times.

45 The pivot connection 26 allows the storage container 14 to be moved pivotally into the withdrawal positions "A" and/or "B" shown by dot and dash lines 39 and 31 respectively in Fig. 2. When the storage container is moved into either withdrawal position the container is moved entirely clear of the depositing slot 28 so that it is 50 possible to pick up the one cigarette lying therein for use. Even in the withdrawal position cigarettes in the storage container are fully enclosed, by the cover 27 at the top and by the side wall 12' of the block 12 at the bottom.

55 The cigarette dispenser so far described is preferably arranged so that the storage container is normally in the vertical position shown so that a cigarette 20 is exposed each time the container is moved to the "A" and/or "B" positions. However, it will work equally satisfactorily to dispense a cigarette if the container is normally in the "A" position and is swung into the "B" position or vice versa.

Fig. 3 discloses a slightly modified form of the 60 present invention substantially like the dispenser of Figs. 1 and 2, but including a flat spring 32 suitably secured in a channel 33 in a base 10a with the upper end fitting into a slotted lug 34 lanced out of the side of the finger 21. Preferably the lower end of the spring 32 is provided 65 with a curled section 35 fitting into a round chan-

nel 33a while the flat section of the spring is at its lower end prevented from turning by upstanding lugs 36 preferably made integral with the base 10a. The upper end of the spring is normally bowed into the position shown by dot and dash lines 38 whenever the storage container 14 is moved to a dispensing or withdrawal position and the spring normally causes the container to return to the upright or nonwithdrawal position when released. Fig. 3 also discloses a modified 10 form of pivot connection merely including screws or studs 39 passed through the fingers 21 at both sides of the storage container into the block 12. 15

Fig. 4 is very similar to Fig. 3. However, it shows a slightly modified form of spring structure 40 for returning the storage container to the nonwithdrawal position. This form of the invention includes a spring 41 of an inverted substantially T-shaped form held on the base 10 by a screw 42 and including upstanding fingers 43 20 and 44 engaging ears 45 and 46 respectively lanced outwardly on the finger 21.

Fig. 5 shows a slightly modified form of depositing arrangement. The general construction is the same as that hereinbefore described in detail 25 in connection with Figs. 1 and 2. The main point of difference is the provision of a depositing slot 28a and/or 28b at the sides instead of at the top of the block 12. Preferably the bottom is provided with a slightly curved section 11a forming 30 a pocket of "pickup" channel 11b to receive the cigarette. Also, the depositing slots 28a and 28b are preferably provided with slightly angular and downwardly inclined walls 50 so that the cigarette will roll by gravity from the channel 35 28a into the "pickup" channel 11b. A "pickup" channel similar to 11b may be made coextensive with the angular wall 50 if so desired.

Either of the spring arrangements shown in 40 Figs. 3 and 4 may be used for that form of the invention shown in Fig. 5 just described in detail.

The structure shown in Fig. 5 is advantageous when the spring means of Figs. 3 and 4 are used since it is not necessary to remove the cigarette from the depositing channel 28a or 28b while the 45 storage container 14 is held in a position against the pressure of the springs or even when the container is returned to its normal vertical position.

Movement and stopping of the storage container 50 14 into the nondepositing position is effected by the spring structures disclosed and described in connection with Figs. 3 and 4. Movement of the storage container 14 into the depositing positions may be limited by pins 49 shown in Figs. 1 and 2, 55 by the slight shoulders or walls 47 on the end wall 22 as shown in Fig. 3, or by the lower edge 48 of the container engaging the angular wall 50.

Other variations and modifications may be made within the scope of the present invention, 60 and portions of the improvements may be used without others.

Having described the invention, what is claimed as new is:

1. In a cigarette dispenser the combination of 65 a base having a depositing channel and a pickup channel at a lower level than said depositing channel; a downwardly inclined wall defining said depositing channel and extending toward said pickup channel; and a storage container having a bottom opening, pivotally mounted on said base and movable into depositing and nondepositing positions relative to said depositing channel; said container and said base alone 70 maintaining a cigarette in said depositing chan- 75

nel, whereby a cigarette may roll by gravity from the depositing channel to the pickup channel when said storage container is pivoted away from said depositing channel.

- 5 2. In a cigarette dispenser the combination of a base having a depositing channel and a pickup channel at a lower level than said depositing channel; downwardly inclined means extending from said depositing channel toward said pickup channel; and a storage container having a bottom opening being disposed above said base and movable relative thereto to deposit a cigarette in said depositing channel; said container and said base alone maintaining a cigarette in said depositing channel; whereby a cigarette may roll by gravity from the depositing channel to the pickup channel when said storage container is moved away from said depositing channel.
- 10
- 15

3. In a cigarette dispenser the combination of a base having a depositing and a pickup channel at a lower level than said depositing channel; a downwardly inclined surface extending from said depositing channel to said pickup channel; a storage container having a bottom opening pivotally secured to said base so as to oscillate about said base for depositing a cigarette in said depositing channel, said base fully closing said bottom opening when said container is in normal and nondepositing position, whereby a cigarette may roll by gravity from the depositing channel to the pickup channel when said container is pivoted away from said depositing channel.
